UNITED STATES PATENT OFFICE.

FRANK W. CAMP, OF SAN FRANCISCO, CALIFORNIA.

APPARATUS AND METHOD FOR COATING PILES.

Application filed February 21, 1921. Serial No. 446,662.

To all whom it may concern:

Be it known that I, FRANK W. CAMP, a citizen of the United States, and resident of the city and county of San Francisco, State 5 of California, have invented new and useful Improvements in Apparatus and Methods for Coating Piles, of which the following is a specification.

My invention has for its object the application of a coating of concrete or the like around a submerged pile, for the purpose of protecting the same from the ravages of the teredo, or other marine deterioration, and also for reinforcing the strength of the 15 pile or creating a concrete cylinder in place of and around the axis of the pile as a substitute supporting member where the pile strength has been greatly or entirely lost.

Reference is herein made to my copending 20 applications, Serials 356,966 and 356,967, respectively, and which applications were filed with the Commissioner of Patents on Feb. 7, 1920, wherein I have set forth other apparatus and method for coating piles.

My present invention has for its particular object means and method of applying, using and removing a mold form concentric about the axis of a pile or the like to be coated whereby the said form may be quickly 30 and easily detached from the concrete or other molded material after the latter has set, and this is accomplished by the disconnection of certain fastenings and the raising of the mold form in an upward direction as 35 by cables, and coincident with which movement the sectionalized expansible diaphragm in the bottom mold form bites into or pivots on the surface of the pile, the individual leaves of the said diaphragm acting at such 40 times as compression struts to force outward the lower portion of the mold form and which said lower portion carries with it the several longitudinal members, one or more sections of which depending upon the bolt- 45 ing in longitudinal alignment and undersaid strut action, are stripped freely from the surface of the molded concrete. In this way the bottom sections of my mold are more easily and freely removed than heretofore, 50 whereby I am enabled to more easily and economically apply a coating of concrete to a pile and to a considerable depth.

Other objects will appear from the specifications and drawings as follows:

Figure 1 is a sectional view of my mold form in place around a pile and showing the

concrete material, sand gasket and expansible diaphragm bottom,

Fig. 2 is a plan view of Fig. 1.

Fig. 3 is similar to Fig. 1, with the mold 60 form in the act of being removed from the completed coating.

Fig. 4 is an enlarged detail of one of the 65 expansible diaphragm compression struts and canvas covering therefor.

Fig. 5 shows in detail the manner of assembling the diaphragm struts about one of the segments of a mold section.

Fig. 6 is a side view of Fig. 1 with the assembled mold form in place about the pile 70 showing the means and manner of fastening and unfastening along the lines of separation of the form after the setting of the concrete coating and while assembled thereabout.

Fig. 7 is a section on the line VII—VII of 75 Fig. 3.

Throughout the figures similar numerals refer to identical parts.

A complete mold form is shown in section 80 in Fig. 1 whose principal parts comprise a plurality of sections, each section in turn comprising a plurality of half sections or segments, thus in the figure 7, 9 and 11, 13 and 15, 17 are each half sections or segments; 7, 9 forming one section; 11, 13 forming a second section, and 15, 17 a third section, in this case the bottom section.

A pile to be coated is shown by the numeral 1, the concrete coating to be applied 90 thereabout is indicated by the numeral 2; the water surface is shown at 3 and the mud line at 4. It is essential to carry the coating 2 below the mud line 4 to properly protect the pile against ravages of the teredo, and 95 for this purpose the excavation around the pile and below the mud line as at 6 may be accomplished by water jets as set forth in my copending applications above referred to. The mold form consists of a plurality 100 of segments 7, 9, and 11, 13, 14 and 15, 16, 17, 18 and as many more as may be required which are assembled about the pile 1, leaving a concentric space to be filled with a concrete mixture 2. The several segments 105 7, 11, 15 and 8, 12, 16 and 9, 13, 17 and 10, 14, 18 are assembled respectively in alignment so that the vertical joints are continuous throughout the plurality of sections; that is, the entire mold form may be separated along the vertical joints as 19, 20, 110 Fig. 2, and may be hinged outward on the

vertical lines 21, 22 and away from the completed coating, and when the joint fastenings 32, 33 are released the entire form may be swung away from the completed coating 5 as shown in Figs. 3 and 7.

In the lowermost sections 15, 16, 17 and 18 I provide an expansible diaphragm consisting of a plurality of finger members 23 which may be tapered or pointed if desired 10 and which bridge the space from the mold sections 15, 16, 17, 18, to the pile 1. These are made of relatively heavy metal so as to resist the strains due to the weight of the concrete, which strains occur when the form 15 is being stressed by the upward pull of the cables 24 and 25 and whereby the form is pushed away from the concrete 21 after the latter has set. These finger pieces are bent over as at 27, Figs. 1, 3, 4, for the purpose of 20 keeping the body of the fingers entirely free from the pile surface and to provide an end which is formed to bite into the pile when the cable 24 is pulled up, as in Fig. 3.

At 28 is shown a covering for the finger 25 members which I prefer to form of canvas, green cow hide or the like to provide a suitable bottom on which the sand gasket 29, consisting of gravel the size of a pea or sand or the like on which the concrete mixture 30 is deposited, and which prevents the leakage of the said concrete mixture out of the form and at the same time enables the bottom members of the form and diaphragm 35 to separate freely from the pile on a clean line of cleavage 30 which line is the bottom of the final finished concrete covering 2.

As the form is drawn upward and outward by the cables 24 and 25, the expansible diaphragm formed of the supporting strut 40 members 23 and the canvas covering 28 collapses around the bottom and remaining in contact with the pile until the form has sprung outward as in Fig. 7 a sufficient amount to allow the fingers 23 to drop downward into the dotted position 31, Fig. 3, when the sand gasket 29 will empty freely from the mold form and the entire apparatus may be drawn or float to the surface and be ready for reassembling and for further use about another pile.

The manner of attaching the finger members 23 to the form sections is indicated clearly in Figs. 4 and 5. A reinforcing flange 40 similar to the flanges 35 and 36 55 is formed as a band segment around the section member 15 and is secured thereto by the eyebolts and nuts 41. A pintle 42 curved concentric with the segment 15 is then passed through the eyes of the said bolts and 60 also through the eye 43 of the finger members 23.

To form the eye 43 I bend or twist the body of the member 23 at right angles and on each side thereof and over the pintle and 65 between the adjacent eyebolts I slip the

bushings 44, 44. By this construction the finger members are free for the requisite lateral movement to enable them to adapt themselves to the irregularities of the pile.

When the form is first assembled about 70 the pile a series of pins indicated at 32, 33, Fig. 2 are joined together by cables or chains as indicated in my copending application so that by withdrawing the chains of these two groups of vertical aligned pins the vertical 75 joints 19, 20 of the entire assembled form are freed from restraint; the several sections, however, remaining in vertical assembly with each other and securely held together by the bolts as 34, flanges 35 and 36. 80 The horizontal jointing of the mold form as on the line 38 Fig. 1 is for the purpose of facilitating the assembly of the mold above the water line 3, it being understood that sections 15, 16, 17, 18 with the expansible 85 diaphragm and canvas covering are first assembled above the water line and retained in circular assembly by the pins as 32, 33 and thereafter segments 11, 12, 13, 14 are superimposed thereon, the flange 35 forming 90 a dovetail alignment at 38 and the flanges 35, 36 being bolted together by a series of holding bolts 34; and thereafter in similar manner segments 7, 8, 9, 10 are superimposed thereon and assembled and similar 95 segments are built up and coincident therewith the mold form is lowered to a position below the mud line 4 but with its top extending above the water line 3. Concrete mixture 2 is fed into the mold form as it 100 is built up and being lowered so that at all times the concrete mixture within the mold form extends above the water surface 3. In this way an internal pressure is at all times maintained in excess of the external pressure so that there is no tendency for a seepage of sea water through the expansible dia- 105 phragm, the sand gasket 29 or joints of the segments and sections and the concrete within the form hardens in perfect condition, leaving a finished coating on the pile as indicated at 2 in Fig. 3.

I claim:

1. Apparatus for applying a concrete coating to piles comprising a plurality of 115 sections constituting a mold form, holding means for said form, a bottom diaphragm consisting of a plurality of radially disposed members pivotally joined to the lower end of said form, said members being of 120 such length as to contact with and to form an acute angle with said pile, the contacting ends of said members being bent inward toward said pile whereby they embed themselves in said pile and form a fulcrum to 125 cause the mold sections to swing outward when said sections are lifted, means whereby said holding means may be released from above, and cables for lowering and raising said form.

2. Apparatus as set forth in claim 1 and a cover of flexible material extending over the diaphragm.
3. Apparatus as set forth in claim 1 and a cover of flexible material extending over the diaphragm and adapted to contact entirely around the periphery of the pile.
4. Apparatus as set forth in claim 1 and a cover of flexible material extending over the diaphragm and adapted to contact entirely around the periphery of the pile and said cover secured to the mold form.
5. Apparatus as set forth in claim 1 wherein the said sections comprise a plurality of segments in axial alignment 15 whereby the form may be parted longitudinally.
6. Apparatus as set forth in claim 2 and a sand gasket on top of said cover.
7. Apparatus as set forth in claim 4 20 wherein the said sections comprise a plurality of segments in axial alignment whereby the form may be parted longitudinally.
8. Apparatus as set forth in claim 7 25 wherein the said sections comprise a plurality of segments in axial alignment whereby the form may be parted longitudinally.

FRANK W. CAMP.
